United States Patent Office.

W. W. JACOBS, OF HAGERSTOWN, MARYLAND.

Letters Patent No. 83,171, dated October 20, 1868.

IMPROVEMENT IN VAPOR-BURNERS.

The Schedule referred to in these Letters Patent and making part of the same.

To all whom it may concern:

Be it known that I, W. W. JACOBS, of Hagerstown, in the county of Washington, and State of Maryland, have invented a new and useful Improvement in Lamp-Burner; and I do hereby declare that the following is a full, clear, and exact description thereof, which will enable those skilled in the art to make and use the same, reference being had to the accompanying drawings, forming part of this specification.

This invention relates to an improvement on a lamp-burner, for which Letters Patent were granted me, dated November 5, 1867.

That burner, like the present, is intended for burning oil without a chimney, by generating gas by the heat of the tube.

In that patent the generator is stationary, and no provision is made for preventing the generation of gas in the lamp by a non-conductor of heat, and no means are provided for raising and lowering or adjusting the generator on the wick-tube, and thereby controlling the flame.

The present invention consists in making the generator adjustable, and in attaching non-conductors both to the generator and to the screw-cap of the wick-tube, as I will proceed to describe.

Figure 1 represents a top view.

Figure 2 is a vertical section of fig. 1, through the line $x x$.

Similar letters of reference indicate corresponding parts.

A represents the screw-cap of the wick-tube.

B is a wooden disk through which the wick-tube passes, which is secured to the wick-tube by two metallic plates, as seen in the drawing.

These metallic plates are marked *c* and *d*.

This disk (of wood or some other non-conductor of

heat) prevents the descent of the heat to the oil in the lamp.

E is the wick-tube.

F is the generator which surrounds the wick-tube, as seen in the drawing.

C is another non-conductor or disk, of wood or other non-conducting substance, secured to the generator by metallic plates *h* and *i*.

The generator is perforated for the discharge of the gas, as seen at *j*, when the gas is ignited.

The generator and the wick-tube form a telescopic joint, which renders the generator adjustable for regulating the flame of the lamp.

The non-conductors keep the burner comparatively cool, so that the generator can be readily adjusted on the tube, and the parts handled without inconvenience.

Having thus described my invention,

I claim as new, and desire to secure by Letters Patent—

1. The annular wooden disk C, secured, between metallic plates *h i*, to the generator F, as herein shown and described, whereby the said generator may be adjusted without inconvenience from heat, the heat radiating from the parts E F, not being conducted by the disk C.

2. The lamp-burner, constructed as described, and consisting of the generator F, perforated at *j*, wick-tube E, annular wooden disks B C, and metallic plates *h i c d*, all arranged and combined to operate in the manner and for the purpose herein set forth.

The above specification of my invention signed by me, this 30th day of January, 1868.

W. W. JACOBS.
